(57) CLAIM

The ornamental design for a wrapping film as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a wrapping film according to the present invention; and,

FIG. 2 is a front view of a second embodiment of the wrapping film, showing the design in use.

Features depicted in the broken lines form no part of the claimed design.

1 Claim, 2 Drawing Sheets
